PUTTER HEAD

Sherwood M. Hanson, S. Main St.,
Sandwich, Ill. 60548

Filed Jan. 10, 1967, Ser. No. 5,366

Term of patent 14 years

(Cl. D34—5)

FIG. 1 is a perspective view of a putter head embodying my new design;

FIG. 2 is an elevational view of the back of the putter head of FIG. 1;

FIG. 3 is an elevational view of the front putting face of the putter head of FIG. 1;

FIG. 4 is a top plan view of the putter head of FIG. 1;

FIG. 5 is an end elevational view of the putter head of FIG. 1; and

FIG. 6 is a cross-section view taken in the plane 6—6 of FIG. 2.

The essential features of my design reside in the spoon-shaped depression on the back of the putter head in combination with those portions of the putter head other than the striking face, all as shown.

I claim:

The ornamental design for a putter head, substantially as shown and described.
